ABSTRACT

A method and associated apparatus for interfacing with envelope handling accessories for a universal multi-station document inserter for performing predetermined functions with envelopes having documents inserted therein by the multi-station document inserter, comprising the steps of providing an accessory interface microcomputer, arranging accessories responsive to output signals from the accessory interface microcomputer in an array, providing envelope sensing means in the array for providing clock signals to the accessory interface microcomputer, storing data words in the accessory interface microcomputer, certain of the data words indicating particular combinations of envelope sensing means for envelope jams and other data words indicating the type of accessory, its output location and providing clock data relating to the particular accessory, and indicating the accessories to be actuated by an envelope entering the array, storing envelope handling programs in the accessory interface microcomputer, and actuating the accessories of the accessory array under control of the accessory interface microcomputer in accordance with the data words stored therein in response to clock signals from the envelope sensing means.

ACCESSORY INTERFACE CIRCUIT FOR
UNIVERSAL MULTI-STATION DOCUMENT
INSERTER

CROSS-REFERENCE TO RELATED
APPLICATIONS

This application is related to U.S. application Ser. No. 394,388 entitled "UNIVERSAL MULTI-STATION DOCUMENT INSERTER" filed July 1, 1982 in the names of Peter N. Piotroski and John M. Gomes, which is assigned to the same assignee as the present invention. The disclosure of the aforementioned patent application is incorporated herein by reference.

PROGRAM APPENDIX

A program listing for a supervisory control program of the type employed in the universal multi-station document inserter of the aforementioned related patent application is set forth as part of the specification at the end of the detailed description and before the claims as Appendix A. A program listing for the accessory interface circuit program is set forth as part of the specification at the end of the detailed description and before the claims as Appendix B.

BACKGROUND OF THE INVENTION

The present invention relates to document inserters, and more particularly to an accessory interface circuit for use in a multi-station document inserter.

Known multi-station document inserters employing document handling accessories such as mailing machines, stackers, zip code markers, envelope deflectors, and the like, generally employ discrete elements and are manufactured and wired for each specific customer application. Each such document inserter is manufactured as virtually a one-of-a kind machine with the attendant high costs associated therewith. Such apparatus typically require many weeks to design and manufacture, require substantial operator training time to operate, and are difficult and time consuming to service. One such multi-station document inserter document inserter is disclosed in U.S. Pat. No. 3,606,728 issued on Sept. 21, 1971 to Sather et al., and assigned to Bell & Howell Co., Phillipsburg, N.J. The accessories used with the known multi-station document inserters are hard wired to the inserter such that a change in the location or function of a particular accessory requires rewiring of the inserter and/or reprogramming thereof.

SUMMARY OF THE INVENTION

It is an object of the present invention to provide an accessory interface circuit for a universal multi-station document inserter.

It is a further object of the present invention to provide an accessory interface for a universal multi-station document inserter in which various document handling accessories may be employed to accommodate different customer applications without requiring reprogramming.

It is a further object of the present invention to provide an accessory interface for a multi-station document inserter which is capable of operating with a variety of different types of accessory document handling stations including, for example, no sealers, power stackers, vertical stackers, three-tier stackers, envelope deflectors, mailing machines, zip code markers and the like, without the need for rewiring or reprogramming the appara-

tus if changes are made in the location and/or function of the accessories.

Briefly, in accordance with the present invention, a method and associated apparatus is provided for interfacing with envelope handling accessories for a universal multi-station document inserter for performing predetermined functions with envelopes having documents inserted therein by the multi-station document inserter, comprising the steps of providing an accessory interface microcomputer, arranging accessories responsive to output signals from the accessory interface microcomputer in an array, providing envelope sensing means in the array for providing clock signals to the accessory interface microcomputer, storing data words in the accessory interface microcomputer, certain of the data words indicating particular combinations of envelope sensing means for envelope jams and other data words indicating the type of accessory, its output location and providing clock data relating to the particular accessory, and indicating the accessories to be actuated by an envelope entering the array, storing envelope handling programs in the accessory interface microcomputer, and actuating the accessories of the accessory array under control of the accessory interface microcomputer in accordance with the data words stored therein in response to clock signals from the envelope sensing means.

Other objects and advantages of the present invention will become apparent from the detailed description considered in conjunction with the preferred embodiment of the invention illustrated in the drawings as follows:

BRIEF DESCRIPTION OF THE DRAWINGS

FIG. 1 is a block diagram showing a universal multi-station document inserter of the type within which the accessory interface circuit of the present invention may be utilized;

FIGS. 2 and 2a through 2g comprise a schematic diagram of an accessory interface circuit in accordance with the present invention;

FIG. 3 is a block diagram showing one possible arrangement for the accessories to be used with the accessory interface circuit; and

FIGS. 4a through 4x comprise a flow chart of the routines and subroutines employed in the program for the accessory interface circuit of the present invention.

DETAILED DESCRIPTION OF THE
INVENTION

Referring to FIG. 1, a universal multi-station document inserter of the type disclosed in the aforementioned related patent application is designated as 10. As described in the aforementioned related patent application, the individual document feeder stations 12 may include a standard feeder (STD.), a high ratio feeder (H.R.), a high speed feeder (H.S.F.), a folder feeder (F.F.), and a burster/folder feeder (B.F.), each of the document feeder stations 12 including a feeder interface circuit 14. An envelope feeder station 16 also includes a feeder interface circuit 18.

As described in detail in the aforementioned related patent application, a supervisory control circuit or central microcomputer 20 interacts directly with a transport interface circuit 22 to activate the transport motor, clutch and brake, and receives pulses from an encoder for control of a transport deck (not shown). The super-

visory control circuit 20 also maintains interactive communication with a central control display 24 over a standard communication line 26. Advantageously the central control display 24 may be a finger touch display switch, such as FLUKE Model 1780A INFOTOUCH display. The supervisory control circuit 20 also communicates with a scanner interface circuit 28 through signal bus 30. The scanner interface circuit 28 communicates with feeder interface circuit 14. Communication between the supervisory control circuit 20 and the feeder interface circuit 14 (documents) and envelope feeder interface circuit 18 (envelopes) and an accessory interface circuit 32 in accordance with the present invention is maintained over the signal bus 30. Typical document handling accessories 34 which may be electrically connected to the accessory interface circuit 32 include conventional no sealers, mailing machines, zip code markers, vertical stackers, power stackers, envelope deflectors, vertical power stackers, three-tier stackers and the like. Communication with and control of the document handling accessories 34 is maintained through the accessory interface circuit 32.

As described in the aforementioned related patent application, the document inserter 10 includes a plurality of serially arranged modules including an envelope feeder station or module and document feeder stations including feeder modules and a burster folder station. A computer generated forms feeder feeds continuous form control documents having coded marks thereon to the burster folder for separating and folding. The coded marks on the control documents are sensed by a control scanner. Thereafter, the serially arranged feeder station sequentially feed the necessary documents onto a transport deck at each station as the control document arrives at the respective station to form a precisely collated stack of documents which is transported to the envelope feeder. The transport deck includes a ramp feed so that the control document always remains on the top of the stack of advancing documents. Such a transport deck is used in the INSERTAMAX III Mail Inserter available from Pitney Bowes Inc. of Stamford, Ct. However, it should be understood that the transport deck may be of other types such as that used in the INSERTAMAX II Mail Inserter available from Pitney Bowes Inc. of Stamford, Ct. or the transport deck disclosed in U.S. Pat. No. 3,934,867 issued on Jan. 27, 1976 and assigned to Pitney Bowes Inc.

The collated stack of documents is inserted in an envelope at the envelope station and transported to conventional accessory document handling stations 34 of the type previously described. First, envelope is sealed or not sealed as desired by a sealing unit. The necessary postage is then provided by a postage meter such as, for example, Pitney Bowes Inc. Model No. 4255 Postage Meter. The envelopes may then be transported to a single or multi-level stacker.

Referring to FIGS. 2a through 2g the accessory interface circuit is illustrated generally as 32. The accessory interface circuit 32 includes an accessory interface microcomputer 35, which may be a Model 8742 available from Intel Corporation. Address signals are received from the supervisory control circuit 20 over address lines 33 and inputted to the chip select port of the microcomputer 35 from the output of an OR gate 36. An address receive acknowledge signal is provided from the microcomputer 35 to the supervisory control circuit 20 over lead 38. Data signals are received from the supervisory control circuit 20 by the microcomputer 35

over input leads 39. A command signal is received from the supervisory control circuit 20 over lead 40.

Accessory interface circuit 32 includes a pair of port expanders 42 and 44. Port expander 42 is an input port expander which receives clock signals from the photo-cells (P.C.) and microswitches (MMTRP) of accessory document handling devices over input leads 46 after the clock signals are first applied to Schmitt trigger inverters 47. Port expander 44 is an output port expander 44 which provides output signals to the accessory document handling devices, see FIG. 1, over output leads 48. The input and output port expanders 42 and 44 may be Type 8243 available from Intel Corporation. Output leads 49 from the microcomputer 35 provide output signals to operate a relay for motor control and solenoids 50 for the belt stackers of the accessories 34, see FIG. 1. Leads 51 from the microprocessor 35 are coupled to the control ports of the input port expander 42 and the control ports of the output port expander 44 for the bidirectional transmission of data and the selection of input or output data control. An external timing circuit 52 provides start and stop timing signals to the microcomputer 35 over leads 54 for the zip code or envelope deflector, see FIG. 1.

Also connected to output lines 48 of the output port expander 44 are LED's actuated by drivers 57 to provide visual indication of the condition of individual accessory devices 34. Advantageously, the input lines 46 to the input port expander 42 includes LED's 58A and 58B and associated drivers 60A and 60B for field testing of the input ports of the input port expander 42. Likewise, the output leads 49 of the microprocessor 35 include LED's 62 and drivers 64 for field testing of the output ports of the microcomputer 35.

Referring to FIG. 3, a particular arrangement of accessory document handling devices 34 in accordance with the present invention is illustrated. However, it should be understood that any one of a variety of configurations of conventional accessory document handling devices can be used based on customer preference and in accordance with a data table entered into a configuration PROM in the supervisory control circuit 20. The array of accessory document handling devices includes a no sealer 70, a first mailing machine 72, a first vertical stacker 74, a second mailing machine 76 and second through seventh vertical stackers 78 through 88. A zip code or envelope deflector 90 and a vertical power stacker 92 are also included. Adjacent to the second mailing machine 76 is an edge marker 94. No sealer module 70 is employed to prevent or stop the sealing of envelopes received from the transport deck after passing through the array of feeder stations. Normally, stuffed envelopes containing inserted documents from the feeder modules are sealed, but on certain occasions, it is desirable not to seal the envelopes and the module 70 operates to prevent such sealing, for example, by using a solenoid driven deflection plate. As previously noted, the mailing machines 72 and 76 may be Models 4255 available from Pitney Bowes Inc. Multiple mailing machines facilitate the use of a postage break if the documents in an envelope exceed a predetermined number indicating additional postage is necessary. The various vertical stackers 78 through 88 may provide stacking by type, for example, zip sorting, overweight, for example over 3 ounces, sorting by mismatch, and sorting by control document code. Edge marking module 94 marks the edges of certain envelopes.

Zip deflector 90 is primarily employed with pre-sorted mail to indicate the beginning or end of another batch of documents having a different zip code. This is also true for the edge marker unit 94.

In FIGS. 4a through 4x, there is shown in flow chart form, the various routine and subroutines employed in the operation of the software resident in the ROM of the microcomputer 35 of the accessory interface circuit 32. When the document inserter is turned on (Power Up) the accessory interface circuit 32 enters into an initialization routine designated as RINIT (FIG. 4A) wherein the RAM of the microcomputer 35 is cleared of data and following this the RAM receives data from the supervisory control circuit 20 in the form of Jam Words and Output Words. The NXTONE Routine (FIG. 4D and E) increments through various RAM locations to determine if information exists at any RAM location. Incrementing proceeds through two tables containing Output Select Words from the supervisory control circuit 20. Each time a RAM location is checked for information, a check is also made of certain combination of photocells and microswitches (Jam Words) to determine if there is a jam, i.e., if a combination of two (2) photocells and/or microswitches as designated in the configuration PROM is occurring. The Done 10 Subroutine (FIG. 4C) is the end of the NXTONE Routine shown in FIGS. No. D and E. Further, within the NXTONE Routine are various other subroutines including SETBIT (FIG. 4P) which expands the Binary Code for the detection of photocell and microswitch status in the LOOKPC Routine (FIG. 4N) which looks for a particular photocell as set by the decoded Binary Code.

The CKDCOD (FIG. 4F) Routine decodes the words found in the tables in RAM, which pertain to the envelopes selected output functions or accessories, to interrogate the status of the next expected clock (P.C. or microswitch) employing the SETBIT and LOOKPC Subroutines. Also CKDCOD employs a DECNT Subroutine (FIG. 4G) which decrements the count of the expected clock stored with the coded information in the RAM tables and an ERACIT Subroutine (FIG. 4B) which erases the data in the RAM once the clock data has been decremented to zero and it is no longer needed. If the clock count is zero the CKDCOD Routine branches to an OUTIT Subroutine (FIG. 4H) which checks the various bits in the RAM table once the clock count is zero to determine the type of accessory device and therefore the next operation to be performed thereby. Specifically if a bit is present at location 7 of the 8 bit table 1 Word, the Routine WIPPIT (FIG. 4K) is commenced, indicating a no sealer, a vertical stacker or mailing machine accessory. If bits are present at both locations 6 and 7 of the 8 bit table 1 Word or at locations 7 and 5 of the 8 bit table 1 Word, the Routine 3 TIER B or 3 TIER C (FIG. 4J) is undergone to turn an accessory on or off. If a bit is only present at location 6, the Routine ZIPDEF (FIG. 4M) is commenced for the zip code deflector to deflect an envelope to indicate the end of one batch of zip codes or the beginning of another batch of zip codes. If a bit is only present at location 5, the Routine EJMARK (FIG. 4L) is commenced to mark the edge of an envelope.

The SETRAM Routine (FIG. 4T) takes the cyclic two (2) eight bit words of information, converts it into two words containing accessory identification information and clock count output port numbers and inserts this information into the table 1 and 2 portions of RAM

for the microcomputer 35. The RELOCK Subroutine (FIG. 4X) is commenced to locate empty data locations in tables 1 and 2 of the RAM. If no more data is present for entry into the RAM tables 1 and 2, the DONE 6 Subroutine (FIG. 4V) is commenced to restore the pointer positions, the accumulator, and enable the interrupt.

The OUTWRD Routine (FIG. 4S) stores the Output Select Words sent from the supervisory control circuit 20 in RAM of the microcomputer 35 upon initialization. The JMWORD Routine (FIG. 4R) stores the Jam Words sent from the supervisory control circuit 20 in RAM of the microcomputer 35 upon initialization.

The JMCHEK Routine (FIG. 4D) is commenced during each reading of the RAM tables 1 and 2 for Jam Word and clock data (during NXTONE) to determine if there are any combination of clocks (photocells and/or microswitches) which are presently covered by an envelope thereby indicating a jam condition.

The OFFIT Subroutine (FIG. 4V) is used by the WIPPIT, 3TIER B, 3TIER C, ZIPDEF and EJMARK Routines to turn off the outputs of the output port expander 44. The OUTPUT Routine (FIG. 4Q) is used by the WIPPIT, 3TIER B, 3TIER C, ZIPDEF and EJMARK Routines to turn on the outputs of the output port expander 44.

Finally, the IBFEND Routine (FIG. 4W) is commenced in response to information sent by the supervisory control circuit 20 to check the data input buffer for commands or data. If it is a command and bit 6 is high, JAM Word data will be sent. If it is a command and bit 3 is high Output Select Word data will be sent. The absence of a bit at either location results in commencement of the RELOOK Routine of FIG. 4X.

It should be understood that the particularly accessory configuration shown in FIG. 3, and the sequence of operations has been stored in the data table of the configuration PROM contained in the supervisory control circuit 20. Upon initialization, this data is transmitted to the RAM in the microcomputer 35. The accessory interface circuit 32 actuates the specific document handling accessory in the proper sequence in accordance with the data received from the supervisory control circuit 20 during initialization and prior to an envelope entering the accessory array.

Data is received from the supervisory control circuit 20, see FIG. 1, in accordance with the data table stored in the configuration PROM. As previously noted and as discussed in the aforementioned related patent application, the data specifying the accessories to be used and their sequence of operation on specific coded documents, as well as jam data, are written into the data table of a configuration PROM, see U.S. Pat. No. 4,497,040, issued Jan. 29, 1985 in the names of Peter N. Piotroski and John M. Gomes entitled, METHOD AND APPARATUS FOR CUSTOMIZING A MULTI-STATION DOCUMENT INSERTER, assigned to the same assignee as the present invention.

During Power Up, data in the form of JAM Words is sent to the accessory interface circuit 32, along with address bits ADRF and ADRA, which are decoded and loaded into the RAM of microcomputer 35. Thereafter, as an envelope with certain coded documents inserted therein leaves the inserter transport deck and is rotated for entry to the accessory array, e.g., by a turntable, the supervisory control program sends data, e.g., in the form of two eight bit words or two bytes, along with ADRF and ADRA bits to identify the accessory inter-

face circuit 32, to the microcomputer 35 over data leads 39, see FIG. 2.

Both or one of these two data words identifies the type of accessory or accessories to be actuated. From these 8 bit words, two more words are created and stored in RAM tables 1 and 2. The first word describes the specific output port location of the output port expander 44 and the type of accessory. The other word identifies the clock count associated with that particular accessory and a clock count to be decremented to zero for actuation of the particular accessory associated therewith. The clock inputs 1-15 and Z.D.P.C. as seen in FIG. 3 correspond to the photocells and microswitches of the accessories 34 and supply input signals to the input port expander 42 as shown in FIG. 3.

The output port expander 44 of FIG. 3 turns the accessories 70-92 on and off under control of the microcomputer 35 programmed in accordance with the accessory interface circuit program set forth in the Appendix B. Initially, two data words from the supervisory control circuit 20 are loaded into the RAM of the microcomputer 35 each time an envelope enters the accessory array, shown in FIG. 3. As long as the particular envelope is being transported through the accessory array its associated data words (Table 1 word—accessory identification and output port numbers and Table 2 word—(clock count) are retained in the tables in RAM. Upon completion of the functions on a particular envelope, the data words associated therewith, which were stored in tables in the RAM of the microcomputer 35, are erased by the ERACIT Routine of FIG. 4B. Additionally, the program stores data regarding the envelopes in the array and being processed

in RAM. Parallel pointers scan the associated accessory and clock data words stored in the RAM Tables 1 and 2 and the proper output port of the output port expander 44 is energized when the clock count for a particular envelope has been decremented to zero. At this point, the accessory interface circuit program looks at the corresponding data stored in the table associated with the clock word to determine the type of accessory and output location to energize the proper output port.

The storage of the two data words in the data Tables 1 and 2 in the RAM is dynamic in that upon completion of the functions with respect to a particular envelope, its two identifying data words are erased. The clock signals are supplied from the photocells and microswitches of the accessories 70-92 as seen in FIG. 3 by the blocking of the photocells and the tripping of the microswitches by an envelope. Upon a particular clock data word being decremented to zero, its associated data word is read and the operation performed on the envelope in accordance with the outputs from the microcomputer 35 which result in an output at the desired output port of the output port expander 44 as seen in FIG. 3.

The specific Routines and Subroutines for accomplishing the aforementioned operation of the microcomputer 35 have been previously described with reference to the flow charts in FIG. 4.

It should be understood by those skilled in the art that various modifications may be made in the present invention without departing from the spirit and scope thereof as described in the description and defined in the appended claims.

 5818 ;
 5819 ;=====

5820 ;
 5821 ;
 5822 ; BUT FIRST — A FEW WORDS OF EXPLANATION. THE FIRST ELEMENT OF A PIECE OF
 5823 ; MAIL IS A CONTROL DOCUMENT WHICH ENTERS STATION 0 (THE BURSTER/FOLDER).
 5824 ; THE CONTROL DOCUMENT CONTAINS A DASH CODE WHICH SPECIFIES WHICH STATIONS
 5825 ; ARE TO CONTRIBUTE TO THIS PIECE OF MAIL AS IT PASSES DOWN THE LINE OF
 5826 ; STATIONS.
 5827 ;
 5828 ; IT IS SOMETIMES DESIRABLE TO MAKE THE DASH CODE SELECT AN ALTERNATIVE SET
 5829 ; OF STATIONS. FOR EXAMPLE, IF THE DASH CODE CAN SELECT STATIONS 3,5, AND 7,
 5830 ; WE WOULD LIKE TO BE ABLE TO TELL THE SYSTEM TO SELECT STATIONS 4,6, AND 8
 5831 ; INSTEAD. THUS A DASH CODE THAT NORMALLY SELECTS STATION 3, WILL NOW
 5832 ; SELECT STATION 4 INSTEAD. LIKEWISE, THE CODE THAT NORMALLY SELECTS STATION 5
 5833 ; WILL NOW SELECT STATION 6, ETC.
 5834

ASSEMBLY COMPLETE, NO ERRORS

What is claimed is:

1. A method for interfacing with envelope handling accessories for a universal multi-station document inserter for performing predetermined functions with envelopes having documents inserted therein by the multi-station document inserter, comprising the steps of:

providing an accessory interface microcomputer; arranging accessories responsive to output signals from the accessory interface microcomputer in an array;

providing envelope sensing means in the array for providing clock signals to the accessory interface microcomputer;

storing data words in the accessory interface microcomputer, certain of the data words indicating particular combinations of signals from said envelope sensing means for detecting envelope jams and other data words indicating the type of accessory, its output location, clock data relating to the particular accessory, and indicating the accessories to be actuated by an envelope entering the array;

storing envelope handling programs in the accessory interface microcomputer; and

actuating the accessories of the accessory array under control of the accessory interface microcomputer in accordance with the data words stored therein in response to clock signals from the envelope sensing means.

2. The method recited in claim 1, including the steps of:

providing a supervisory control circuit including a microcomputer having certain of said data words stored therein for the accessories of the accessory array;

transmitting the data words to a RAM of the accessory interface microcomputer for use with envelope handling programs stored in the accessory interface microcomputer.

3. The method recited in claim 2, including the steps of:

loading data words corresponding to particular com-

binations of signals from envelope sensing means for indicating envelope jams, the type of accessory, its output location and clock data into the RAM of the accessory interface microcomputer upon power up of the inserter;

loading other data words indicating the accessories to be actuated by an envelope entering the array prior to the envelope entering the array.

4. The method recited in claim 3 including the step of: providing clock input signals to the accessory interface microcomputer from the envelope sensing means in response to envelopes moving past the envelope sensing means.

5. The method recited in claim 4 including the step of: decrementing the clock data stores in the RAM of the accessory interface microcomputer in response to the clock input signals from the envelope sensing means.

6. The method recited in claim 5, including the step of:

providing external timing signals to the accessory interface microcomputer for a zip code deflector accessory.

7. The method recited in claim 2, including the step of:

providing a transfer acknowledge signal from the accessory interface microcomputer to the supervisory control microcomputer upon receipt of data and commands therefrom by the accessory interface microcomputer.

8. The method recited in claim 1, including the step of:

electrically coupling port expander means to the accessory interface microcomputer to expand its input and output ports.

9. The method recited in claim 1, including the step of:

providing a transport system for the accessory array; electrically coupling some of the output ports of the accessory interface microcomputer with the transport system for movement of envelopes along the array in response to output signals from the accessory interface microcomputer.

10. A method for interfacing with envelope handling accessories for a universal multi-station document inserter for performing predetermined functions with envelopes having documents inserted therein by the multi-station document inserter, comprising the steps of:

providing an accessory interface microcomputer; arranging accessories responsive to output signals from the accessory interface microcomputer in an array; 10 providing envelope sensing means in the array for providing clock signals to the accessory interface microcomputer; storing envelope handling programs in the accessory interface microcomputer; 15 providing a supervisory control circuit including a microcomputer having data words stored therein for the accessories of the accessory array; transmitting the data words from the supervisory control circuit to a RAM in the accessory interface microcomputer for use with the envelope handling programs stored in the accessory interface microcomputer, 20 certain of said data words corresponding to particular combinations of envelope sensing means signals for indicating envelope jams, the type of accessory, its output location and clock data into the RAM of the accessory interface computer upon power up of the inserter, 25 others of said data words indicating the accessories to be actuated by an envelope entering the array prior to the envelope entering the accessory array; providing a transport system for the accessory array; providing clock input signals to the accessory interface microcomputer from the envelope sensing means in response to envelopes moving past the envelope sensing means; 30 actuating the various accessories of the accessory array under control of the accessory interface microcomputer in accordance with the data words stored therein in response to the clock signals from the envelope sensing means; 35 decrementing the clock data stored in the RAM of the accessory interface microcomputer in response to the clock input signals from the envelope sensing means; and 40 providing a transfer acknowledge signal from the accessory interface microcomputer to the supervisory control microcomputer upon receipt of data and commands therefrom by the accessory interface microcomputer. 45

11. The method recited in claim 10, including the step of:

electrically coupling some of the output ports of the accessory interface microcomputer with the transport system for movement of envelopes along the array in response to output signals from the accessory interface microcomputer. 55

12. Apparatus for interfacing with envelope handling accessories for a universal multi-station document inserter for performing predetermined functions with envelopes having documents inserted therein by the multi-station document inserter, comprising:

an accessory interface microcomputer for storing data and accessory interface programs; envelope handling accessories arranged in an array; means for electrically connecting certain output ports 65

of said accessory interface microcomputer to said envelope handling accessories; envelope sensing means associated with at least some of said envelope handling accessories for providing clock signals to the accessory interface microcomputer;

means for loading data into said accessory interface microcomputer prior to an envelope entering said array;

said programs stored in said accessory interface microcomputer being operative for actuating said envelope handling accessories in a sequence which is determined in response to the data loaded therein.

13. The apparatus recited in claim 12, including: supervisory control circuit means including a microcomputer having data words stored therein for the envelope handling accessories; and wherein said means for loading data comprises means for loading data words from said supervisory control circuit means into said accessory interface microcomputer for use with the envelope handling programs stored in said accessory interface microcomputer.

14. The apparatus recited in claim 13, wherein: said loading means loads certain of said data words corresponding to particular combinations of envelope sensing means signals for indicating envelope jams, the type of accessory, its output location and clock data into said interface accessory microcomputer upon power up of said inserter.

15. The apparatus recited in claim 14, wherein: said loading means loads other data words indicating the accessories to be actuated by an envelope entering the accessory array prior to the envelope entering said accessory array.

16. The apparatus recited in claim 15, wherein: said envelope sensing means provide clock input signals to said interface accessory microcomputer in response to the detection of the presence of an envelope.

17. The apparatus recited in claim 16, including: means for decrementing the clock data stored in said accessory interface microcomputer in response to clock input signals from said envelope sensing means.

18. The apparatus recited in claim 17, including: a zip deflector accessory; external timing means for providing external timing signals to said interface accessory microcomputer for said zip deflector accessory.

19. The apparatus recited in claim 13, including: transfer acknowledge signal means for communication with said supervisory control microcomputer to acknowledge the receipt of data and commands therefrom.

20. The apparatus recited in claim 12, including: port expander means electrically coupled to said accessory interface microcomputer to expand its input and output ports.

21. The apparatus recited in claim 12, including: a transport system for moving envelopes along said array to the desired accessory; means for electrically coupling said output ports of said accessory interface microcomputer with said transport system for moving envelopes along said array in response to output signals from said accessory interface microcomputer; and

said envelope handling accessories being actuatable in a predetermined sequence in response to the data loaded in said accessory interface microcomputer as the envelopes move along the array.

22. Apparatus for interfacing with envelope handling accessories for universal multi-station document inserter for performing predetermined functions with envelopes having documents inserted therein by the multi-station document inserter, comprising:

an accessory interface microcomputer for storing data and accessory interface programs; envelope handling accessories arranged in an array; means for electrically connecting certain output ports of said accessory interface microcomputer to said envelope handling accessories;

envelope sensing means associated with at least some of said envelope handling accessories for providing clock signals to the accessory interface microcomputer;

said programs stored in said accessory interface microcomputer being operative for actuating said envelope handling accessories in the proper sequence in response to data loaded therein as the envelopes move along said array;

supervisory control circuit means including a microcomputer having data words stored therein for the envelope handling accessories;

means for loading the data words from the supervisory control circuit microcomputer into a RAM of said accessory interface microcomputer for use with the envelope handling programs stored in said accessory interface microcomputer;

said loading means loads data words corresponding to particular combinations of envelope sensing means signals, the location, type and clocks of said envelope handling accessories into said RAM of

said interface accessory microcomputer upon power up of said inserter;

said loading means loads other data words indicating the accessories to be actuated by an envelope entering said array into said RAM prior to the envelope entering the accessory array;

said envelope sensing means being operative to provide clock input signals to said interface accessory microcomputer in response to the detection of the presence of an envelope;

means for decrementing the clock data stored in said RAM of said accessory interface microcomputer in response to clock input signals from said envelope sensing means; and

transfer acknowledge signals means connected to said accessory interface microcomputer for communication with said supervisory control microcomputer to acknowledge the receipt of data and commands therefrom.

23. The apparatus recited in claim 22, including: a transport system for moving envelopes along the accessory array to the desired accessory;

means for electrically coupling said output ports of said accessory interface microcomputer with said transport system for moving envelopes along the array in response to output signals from said accessory interface microcomputer.

24. The apparatus recited in claim 22, including:

data address means for specifying a unique data address for said accessory interface microcomputer.

25. The apparatus recited in claim 22, including: a zip deflector accessory; external timing means for providing external timing signals to said interface accessory microcomputer for said zip deflector accessory.
